DESIGN FOR A SHOE

Dominick J. Calderazzo, Dolgeville, N. Y.

Application December 17, 1938, Serial No. 81,835

Term of patent 3½ years

To all whom it may concern:

Be it known that I, Dominick J. Calderazzo, a citizen of the United States of America, residing in Dolgeville, county of Herkimer, and State of New York, have invented a new, original, and ornamental Design for a Shoe, of which the following is a specification, reference being had to the accompanying drawing, forming part thereof.

Fig. 1 is a plan view of a shoe showing my new design.

Fig. 2 is a side elevational view thereof.

I claim:

The ornamental design for a shoe, substantially as shown.

DOMINICK J. CALDERAZZO.
